CONDENSING UNIT

Charles P. Russell, Dayton, Ohio, assignor to
 Chrysler Corporation, Detroit, Mich., a corpora-
 tion of Delaware

Application October 29, 1942, Serial No. 463,765

5 Claims. (Cl. 312—1)

My present invention relates to the construction and arrangement of a condensing unit, the invention comprising means whereby reduction in material is afforded, thus reducing the cost of construction and shipping the condensing unit. An object of the present invention is to reduce the cost of materials and labor for furnishing condensing equipment for use in connection with a refrigerating system or an air conditioning system.

The principal object of the present invention is to provide means whereby a sheet metal cabinet customarily provided to surround condensing units for the purpose of excluding foreign objects from the unit and isolating noises, or to provide means to direct a stream of air about the condensing unit to carry away the heat of compression, is rigidly braced to such an extent as to support the weight of a motor compressor unit through a minimum of light weight bracing angles. The object of the present invention is so to brace the sheet metal sides of the cabinet that the sides of the cabinet alone are rendered capable of supporting the weight of the motor compressor unit. Stated in another fashion, the object of the present invention is to provide a system of braces for a sheet metal cabinet such that the weight of a heavy motor-compressor unit suspended from the braces within the cabinet is transmitted to the floor of the enclosure within which the condensing unit is positioned through a large portion of the sheet metal walls whereby the sheet metal walls are rendered capable of supporting the weight and the cabinet may be formed without corner braces or other heavy members as heretofore provided for supporting the weight of the motor-compressor unit.

The foregoing objects and advantages of the present invention will be more readily understood by reference to the following specification and accompanying drawings wherein like numerals refer to like parts throughout.

In the drawings, Fig. 1 is a front view of a form of condensing unit embodying the present invention;

Fig. 2 is a horizontal section taken substantially along line 2—2 of Fig. 1;

Fig. 3 is a partial vertical section taken substantially along line 3—3 of Fig. 1; and

Fig. 4 is a further partial vertical section taken substantially along line 4—4 of Fig. 1.

The invention is shown in a condensing unit embodying the principle of air cooling of the condenser, but it is to be appreciated that the same invention may be incorporated in a con-

densing unit embodying the principle of water cooling of the condenser. The condensing unit comprises a cabinet formed entirely of sheet metal and having side walls 10 and 11 and a rear wall 12, the front of the cabinet being substantially entirely open and adapted to position an access door (not shown) for the purpose of enabling assembly of the equipment therein and servicing of the equipment. The forward edges of the side walls 10 and 11 are flanged as shown at 13 and 14, respectively, cooperating with the flanged portion at 13' of a front top wall 12' to provide an inwardly offset door-receiving space as clearly indicated in Fig. 1. The flanged portions of the side walls extend substantially from the top to the bottom thereof and provide stiffening columns adjacent the sides of the open front so as further to increase the rigidity of the sheet metal. The cabinet may be formed by bending a single sheet of metal at the vertical corners 15 and 16 to provide the forwardly extending side walls and the rear wall, and by welding a bottom wall 17 to the lower edges of the vertical walls, and a top cover may be welded or otherwise fastened to the upper edges of the vertical walls. The cabinet may also be formed by other methods. The specific method of forming the cabinet is immaterial to the present invention, it being the result of any suitable method of formation that a rectilinear cabinet having an open front is provided, the cabinet being distinguished by the absence of angle bars heretofore used to brace the corners of the cabinet or to join the edges of the sheet metal portions to each other.

35 In the illustrated embodiment of the cabinet a side wall thereof is provided with outwardly extending flanges 20 surrounding openings to receive air propellers (not shown) driven by motors 21 supported upon brackets 22, the propellers 40 being adapted to force air through the cabinet or to draw air from the cabinet for the purpose of carrying heat away from the equipment positioned therein, and also to carry heat from the air cooled condenser coil 23 positioned across an opening provided in the top wall of the cabinet. The condenser coil 23 is connected in refrigerant flow relationship to a motor-compressor unit 24 suspended within the cabinet and to a liquid receiver 25 positioned within the cabinet through suitable connecting pipes (not shown) as is well known in the art. The condensing unit is adapted to be connected by other suitable connecting pipes (not shown) to an evaporating unit adapted to function as an air conditioning or refrigerating surface in any of the usual manners. The

present invention is sufficiently illustrated without illustrating details of the refrigerant conducting system.

The motor-compressor unit may be of any form of arrangement, that illustrated being more fully disclosed in the patent to Neeson, No. 2,204,510, issued June 11, 1940, and comprises a very considerable amount of cast iron and other heavy materials. In order to support this heavy unit by the sheet metal walls alone, I have provided means to distribute the weight and brace the weight-supporting portions of the sheet metal walls through the medium of a minimum number of light weight angle bars. For this purpose I provide a horizontal channel bar 30 extending horizontally within the top portion of the casing, the channel bar being fastened to the upper portions of the side walls of the condensing unit by bolting its ends to short angle bars 31 and 32 fastened to the side walls. The angle bars may be welded to the side walls as shown with respect to angle bar 31 or bolted thereto as shown with respect to angle bar 32. The brace 30 is preferably slightly forward of the central vertical plane so as to be somewhat closer to the columnar portions 13 and 14 than to the rear wall 12, so that the stresses from beneath the angles 31 and 32 will be taken up sooner by the columnar portions 13 and 14 than by the edge corners 15 and 16. A short angle bar 33 is fastened horizontally to the upper portion of the rear wall 12 within a region closer to the edge 16 than the edge 15, the center of the angle 33 being substantially the same distance from the corner 16 as the center of the angle 32. The angle bar 33 provides a forwardly extending horizontal ledge upon which is supported the rear ends of a pair of bars 34 extending in parallel relationship normal to the rear wall 12 toward the front of the unit. The bars 34 are preferably in the form of Z-bars, as illustrated, and the relative height of the angle bar 33 to the brace 30 is such that the lower horizontal legs of the bars 34 may be fastened to the top of the angle bar 33 and the upper horizontal legs of the bars 34 may be fastened to the under side of the brace 30. The lower horizontal legs of the bars 34 face inwardly to provide means whereby a flat bar 35 may be supported to bridge the gap between the bars 34, the flat bar being positioned by sliding the same longitudinally from the front toward the rear of the cabinet. The flat bar 35 is secured to the bars 34 by bolts 35'. The bars thus form a rigidly braced cabinet structure capable of supporting considerable weight suspended from the bar 35, such as the motor-compressor unit 24 which is suspended by a single bolt 36 freely rotatable within an opening in the bar 35 and fastened to the top of the motor-compressor unit substantially in alignment with its vertical axis of gravity. The arrangement is preferably such that the suspension member 36 is slightly inwardly from the brace 30 and spaced equally from the bars 34 so that the distance from the suspension member 36 to the center of the angle bar 32 is substantially equal to the distance from the suspension member 36 to the center of the angle bar 33 whereby substantially equal stresses are set up in the side wall 11 and rear wall 12. It will be obvious that the side wall 10 will support less compressor weight than the side wall 11, therefore the side wall 10 may be allowed to support other members such as the motors 21.

As set forth in connection with the aforemen-

tioned patent, it is desirable to permit partial rotation and swinging of the motor compressor unit about its point of suspension during operation, such movements being permitted by the suspension member 36 being freely rotatable with respect to the bar 35, and being capable of being unscrewed slightly from the motor compressor unit so that a rigid tube 37 surrounding the bolt 36 will not bind the compressor against movement. However, it is desirable to prevent any movement of the compressor relative to the cabinet during shipment thereof and for this purpose means are provided for rigidly anchoring the unit to the cabinet walls. Such means comprise a removable bolt 40 passed vertically through an opening in the rear end of one of the bars 34 and a second removable bolt 41 passed vertically through an opening in the forward end of the other of the bars 34, the bolts being received in threaded openings in bosses 42 and 43, respectively, extending laterally from the top of the motor compressor unit. The arrangement is preferably such that the bolts 40 and 41 are diametrically opposed and the bosses protrude laterally from the unit so as to give the greatest possible resistance to rotation of the unit about the suspension member 36. The bolts are preferably surrounded by rigid tubes 44 and 45, respectively, extending between the lower surfaces of the bars 34 and the upper surfaces of the bosses 42 and 43, the tubes being of such length as to be rigidly clamped between the bars 34 and the motor-compressor unit when the bolts are tightened. When the unit is in use the bolts 40 and 41 and the surrounding tubes may be removed so that the unit will be capable of rotation about its vertical axis. In order to prevent swinging of the unit about the suspension member 36 as a pivot, the lower end of the unit is provided with a pair of diametrically opposed vertical bosses 50 and 51 adapted to receive bolts such as bolts 52 and 53 extending from plates 54 welded to an angle bar 55 fastened to the lower portion of the rear wall beneath the angle bar 33. The bolts 52 and 53 are surrounded by rigid tubes such as the tube 56 illustrated in Fig. 4, which are adapted to be clamped between the plates 54 and the bosses 50 and 51 when the bolts are drawn tight. During use of the condensing unit the bolts 52 and 53 and the surrounding tubes are removed so as to render the unit capable of swinging from its vertical position.

As illustrated in Figs. 2 and 4 I have found it desirable to brace the lower corner 60 between the rear wall 12 and the bottom wall 17 by fastening an angle bar 61 within the corner. The angle bar 61 may be omitted in most instances but if the motor-compressor unit is heavier than usual a rigid structure is thus provided without the necessity of providing heavier sheet metal walls and heavier supporting angles at the top of the unit. The angle 61 provides greater protection to the unit since it lies along the edge which usually takes the greatest punishment during shipping of the unit from one point to another, as it is this edge upon which the unit is dropped from a truck to a receiving platform or the like.

Having illustrated and described the preferred embodiment of my invention it should be apparent to those skilled in the art that the same permits of modifications in arrangement and detail. All such modifications as come within the scope of the following claims are considered to be part

75 of my invention.

I claim:

1. A condensing unit comprising a rectilinear sheet metal cabinet having two side walls and a rear wall, the front of said cabinet being open and adapted to position an access door, the vertical forward edges of said side walls being flanged to provide stiffening columns imparting a greater degree of rigidity to the edges of the open front of the cabinet, a horizontal brace fastened to the upper portions of said side walls and extending across the top of the cabinet, an angle bar fastened horizontally of the upper portion of said rear wall and providing a ledge extending forwardly from said rear wall, a pair of bars supported by said brace at their forward ends and by said ledge at their rear ends, a motor-compressor unit and means supported by said pair of bars for supporting said unit in suspended relation thereto, the entire weight of said motor-compressor unit being supported by the sheet metal forming the side and rear walls of the cabinet.

2. A condensing unit comprising a rectilinear sheet metal cabinet having two side walls and a rear wall, the front of said cabinet being open and adapted to position an access door, the vertical forward edges of said side walls being flanged to provide stiffening columns imparting a greater degree of rigidity to the edges of the open front of the cabinet, a horizontal brace fastened to the upper portions of said side walls and extending across the top of the cabinet, an angle bar fastened horizontally of the upper portion of said rear wall and providing a ledge extending forwardly from said rear wall, a pair of bars supported by said brace at their forward ends and by said ledge at their rear ends, a motor-compressor unit and means supported by said pair of bars for supporting said unit in suspended relation thereto, the entire weight of said motor-compressor unit being supported by the sheet metal forming the side and rear walls of the cabinet, said track bars being positioned closer to one of said side walls than to the other so that the angle formed between said rear wall and the closer side wall is rigidly braced by said bars.

3. A condensing unit comprising a rectilinear sheet metal cabinet having two side walls and a rear wall, the front of said cabinet being open, a horizontal brace joining the upper portions of said side walls, a first angle bar fastened horizontally of the upper portion of said rear wall, a second angle bar fastened horizontally of the lower portion of said rear wall beneath said first angle bar, a pair of bars suspended from said brace at their forward ends and supported by and fastened to said first angle bar at their rear ends, a supporting member bridging the space between said pair of bars and fastened at its ends thereto, a single suspension member supported centrally of said supporting member and freely rotatable with respect thereto about a vertical axis, a motor-compressor unit suspended by said suspension member and being thus rotatable

about a vertical axis when in use, removable means to fasten said motor-compressor unit rigidly to said pair of bars to prevent rotation thereof during shipment, and removable means to fasten the lower end of said motor-compressor unit rigidly to said second angle bar to prevent swinging of said motor-compressor unit about said suspension member as a pivot during shipment.

4. A condensing unit comprising a rectilinear sheet metal cabinet having two side walls and a rear wall, the front of said cabinet being open, a horizontal brace joining the upper portions of said side walls, a first angle bar fastened horizontally of the upper portion of said rear wall, a second angle bar fastened horizontally of the lower portion of said rear wall beneath said first angle bar, a pair of bars suspended from said brace at their forward ends and supported by and fastened to said first angle bar at their rear ends, a supporting member bridging the space between said pair of bars and fastened at its ends thereto, a single suspension member supported centrally of said supporting member and freely rotatable with respect thereto about a vertical axis, a motor-compressor unit suspended by said suspension member and being thus rotatable about a vertical axis when in use, removable means to fasten said motor-compressor unit rigidly to said pair of bars to prevent rotation thereof during shipment, and removable means to fasten the lower end of said motor-compressor unit rigidly to said second angle bar to prevent swinging of said motor-compressor unit about said suspension member as a pivot during shipment, said means to prevent rotation comprising a bolt joining the forward end of one of said pair of bars to the top of said motor-compressor unit and a second bolt joining the rear end of the other of said pair of bars to said motor-compressor unit and said means to prevent swinging comprising a pair of bolts joining the opposite sides of the lower end of said motor-compressor unit to said second angle bar.

5. A condensing unit comprising a rectilinear sheet metal cabinet having two side walls and a rear wall, the front of said cabinet being open, a horizontal brace extending between and joining the upper portions of the side walls, an angle bar fastened horizontally of the upper portion of the rear wall, a pair of track bars extending between and connected to the brace and angle bar, a supporting member positioned between and supported by the track bars, suspension means supported centrally of the supporting member, and a motor compressor unit connected to the suspension means, said angle bar being located closer to one side wall than the other, the distance from the suspension means to the center of the angle bar on the rear wall being substantially equal to the distance between the suspension means and a point on said one side wall located at the center of the end of the horizontal brace joined thereto.
